LABORATORY CLAMP

Maynard E. Goldberg, Elmwood Park, Ill., assignor to Laboratory Industries, Inc., Elmwood Park, Ill., a corporation of Illinois

Application August 3, 1950, Serial No. 11,587

Term of patent 14 years

(Cl. D54—13)

To all whom it may concern:

Be it known that I, Maynard E. Goldberg, a citizen of the United States, residing at Elmwood Park, in the county of Cook and State of Illinois, have invented a new, original, and ornamental Design for Laboratory Clamp, of which the following is a specification, reference being had to the accompanying drawing, forming a part hereof, in which:

Fig. 1 is a side elevation of a laboratory clamp showing my new design;

Fig. 2 shows a top plan view of the device illustrated in Fig. 1, the arm on the right of the clamp being omitted for convenience of illustration;

Fig. 3 shows an end elevation of the laboratory clamp looking toward the right in Fig. 1; and

Fig. 4 shows an end elevation looking toward the left as viewed in Fig. 1.

I claim:

The ornamental design for a laboratory clamp, as shown.

MAYNARD E. GOLDBERG.
